ATTORNEYS

UNITED STATES PATENT OFFICE.

OSCAR ALFRED NENNINGER, OF EL PASO, TEXAS.

CONDENSER.

No. 867,833.

Specification of Letters Patent.

Patented Oct. 8, 1907.

Application filed February 6, 1907. Serial No. 356,016.

To all whom it may concern:

Be it known that I, OSCAR ALFRED NENNINGER, a citizen of the United States, and a resident of El Paso, in the county of El Paso and State of Texas, have invented an Improvement in Condensers, of which the following is a specification.

My invention is an improvement in condensers and consists in certain novel constructions and combinations of parts hereinafter described and claimed.

10 Referring to the drawings forming a part hereof, Figure 1 is a front view of my improvement; Fig. 2 is a vertical section; and Fig. 3 is a transverse section on the line 3—3 of Fig. 1.

My invention is adapted to be used in combination 15 with an ordinary house boiler A, supported upon the usual stand a and provided with pipes a' and a'', leading to and from the water back respectively, the pipe a'' being provided with the usual faucet a' for drawing off water from the boiler.

20 The improvement comprises a jacket B for the boiler, and a water condenser C in connection therewith. The jacket B is connected with the boiler in any suitable manner, and is provided with a flanged opening b in the lower end thereof for receiving the pipe a'', and with 25 an air vent b' near its upper end, and on the opposite side from the air vent b' is provided a flanged opening b' at the top and bottom for a purpose to be hereafter described.

The condenser C comprises inner and outer concentric shells or casing c, c', the outer casing being provided with upper and lower flanged openings c' connected in any suitable manner with the flanged openings b' of the jacket, whereby to provide communication between the jacket and the outer casing. At its 30 lower end the outer casing is provided with a short section of pipe c' threaded into one of the branches of a T-joint c' interposed in the pipe a'' before described, the opposite branch of the T-joint having threaded therein a section of relatively small pipe c'' extending through

35 the pipe c' into the inner casing c of the condenser, and provided with a faucet c' as clearly shown in Figs. 1 and 2. The outer casing is also provided with a valved discharge pipe c' at its lower end, and above the discharge pipe is a laterally projecting section of pipe c' of 40 relatively large diameter, into one side of which is threaded a steam inlet pipe c' and through which extends an air inlet pipe c' of relatively small diameter, the steam passing through the inlet pipe c' acting to inject air through the air pipe c' in a well understood 45 manner.

50 A reducing joint c' is threaded on to the upper end of the inner section as shown in Fig. 2, and a T-joint c' is threaded on to the outer end of the reducing joint, one of the lateral branches of the T-joint being closed 55 by a plug c', and the other branch having threaded thereinto the cold water inlet pipe c' of the house

boiler. A cold water inlet pipe c' for the condenser is threaded into the upper branch of the T-joint and communicates with a pipe c' connected with the water main, and provided with a faucet c' for controlling the flow of water therethrough. As will be evident from inspection of Fig. 2, the cold water inlet pipes c', a', extend a considerable distance into the inner casing of the condenser and the house boiler, respectively, in order that they may deliver the cold water below the upper portions thereof.

The house boiler A is provided with a hot water discharge pipe a' provided with a faucet a', by means of which the hot water may be drawn off from the boiler for domestic purposes.

In operation, steam from an ordinary tea kettle, or other vessel on the range, is admitted through the pipe c' into the outer casing c' of the condenser, drawing therewith a supply of air through the pipe c' whereby to aerate the steam. On its entrance into the outer casing, the steam comes into contact with the cool wall of the inner casing c and is partially condensed, the remainder of the steam passing through the openings between the condenser and the jacket into the space between the jacket and the house boiler, where the condensation is completed, the heated air passing out through the vent b', the water of condensation being drawn off through the valve c'. When the water in the inner casing of the condenser becomes heated, cold water is admitted from the main through the pipe c', and the heated water is driven into the house boiler A, passing upward through the reducing joint c', T-joint c', and inlet pipe a', it being understood that the faucet a' is open during the admission of the cold water to withdraw a proportionate amount of heated water from the house boiler. The steam and heated air in the jacket assist also in warming the water in the house boiler. The water may also be withdrawn from the inner casing of the condenser by opening the faucet c' in the pipe c'. 95

I claim:

1. The combination with the house boiler, provided with water circulation pipes for connection with a water back, of a condenser comprising concentric inner and outer casings, said outer casing having a valved discharge pipe, 100 and a relatively large steam inlet pipe, a relatively small air inlet pipe concentric with the steam inlet pipe, said inner casing communicating at each end with the corresponding end of the house boiler, a cold water inlet pipe at the upper end of the inner casing, an outlet pipe at the lower end thereof, a jacket for the boiler provided with an air vent at the top thereof, and communications between the jacket and the outer casing of the condenser at the top and bottom thereof.

2. The combination with the house boiler, of a water 110 condenser comprising concentric inner and outer casings, said outer casing having a valved discharge pipe and a steam inlet pipe, said inner casing communicating at each end with the corresponding end of the house boiler, a cold water inlet pipe at the upper end of the inner casing, a 115

valved outlet pipe at its lower end, a jacket for the boiler provided with an air vent, and communications between the jacket and the outer casing of the condenser at the top and bottom thereof.

5. 3. The combination with the house boiler, of a water condenser comprising concentric inner and outer casings, said outer casing having a valved discharge pipe, and a steam inlet pipe, said inner casing communicating at each end with the corresponding end of the house boiler, a cold water inlet pipe at the upper end of the inner casing and extending thereinto, and a valved outlet pipe at its lower end.

10 4. The combination with the house boiler, of a water condenser comprising concentric inner and outer casings, 15 said outer casing, having a valved discharge pipe, and a

steam inlet pipe, said inner casing communicating at each end with the corresponding end of the house boiler, and a cold water inlet pipe at the upper end of the inner casing.

5. The combination with a house boiler, of a jacket for the boiler, a water condenser comprising concentric inner and outer casings supported by the jacket, said outer casing having a valved discharge pipe and a steam inlet pipe and communicating with the jacket at its top and bottom, said inner casing communicating at each end with the corresponding end of the house boiler, and a cold water inlet pipe at the upper end of the inner casing. 20 25

OSCAR ALFRED NENNIGER.
